CONCRETE BUILDING BLOCK

Harley D. Gustine, Fort Lauderdale, Fla.

Application April 17, 1939, Serial No. 268,434

7 Claims. (Cl. 72—105)

This invention relates to building constructions and more particularly to an improved concrete building block adapted to be used about the marginal portions of a window opening.

5 An object of this invention is to provide a concrete building block which includes metallic means anchored thereto and to which a metal window frame may be secured so that the window structures in localities subjected to termites may eliminate as much wood as possible about the building.

Another object of this invention is to provide an improved building block for use about a window opening which includes a soft metal strip 15 which is anchored to one portion of the block and to which the metal window frame may be firmly secured.

20 A further object of this invention is to provide an improved window frame attaching means in the form of a substantially triangularly shaped strip which is anchored to one side of a concrete building block, the strip having a length substantially equal to the height of the block so that when a series of these blocks are superposed one upon another or placed in side by side relation, a metal frame will be provided to which the metal window frame may be firmly secured.

To the foregoing objects and to others which may hereinafter appear, the invention consists 30 of the novel construction, combination and arrangement of parts as will be more specifically referred to and illustrated in the accompanying drawing, but it is to be understood that changes, variations and modifications may be resorted to 35 which fall within the scope of the invention as claimed.

In the drawing:

Figure 1 is a perspective view of a building block constructed according to this invention, and

40 Figure 2 is an enlarged fragmentary horizontal section through one portion of the block.

Referring to the drawing, the numeral 10 designates generally a concrete building block which is provided with an opening 13 through the center thereof. The block 10 is provided with a straight inner face 11 which at one end thereof has a vertically extending recess 12. The outer face 14 of the block 10 is substantially straight for the greater portion of its length and at one end the outer face 14 is rounded off as at 15. This rounded portion 15 terminates in a concave portion 16 which merges into a flat face 17 disposed at an angle of substantially forty-five degrees to the face 14. One end 18 of the block 55 10 is inset from the adjacent edge of the angled

portion 17 as at 19, the purpose for which will be hereinafter described.

A soft metal strip 20 is adapted to be anchored to the block 10 and comprises a strip which is triangular in transverse section as shown in Figure 2. This strip 20 is adapted to be constructed out of lead or other soft metal and in which screws or nails may be threaded or driven. The strip 20 is anchored to the block 10 by an anchoring member which comprises a stem 21 which is embedded at one end in the triangular strip 20. The inner end of the stem 21 is provided with a V-shaped anchoring portion 22 which is embedded in the block 10. Preferably, the strip 20 is anchored to the block 10 at the time the block 10 is cast or is in plastic form.

The triangular strip 20 is adapted to be engaged by an angle window frame member 23 which is adapted to be secured to the exposed faces of the strip 20 by fastening devices 24 in the form of screws or the like. If desired, a sealing means 25 may be interposed between the angle frame member 23 and the strip 20.

The outer face 14 and the arcuate portion 15 of the block 10 are adapted to have a coating 26 secured thereto, this coating being in the form of stucco or the like. A plaster 27 is adapted to be mounted on the end face 18 of the block 10, the plaster 27 having a thickness substantially equal to the depth of the insert portion of the end face 18 so that in finished form a smooth end face will be provided on the block 10. A wooden strip 28 is adapted to be mounted in the recess 12 on the inner side of the block 10 and a channel member 29 is used to receive the slide members of a Venetian blind which are adapted to engage in the channel member 29. The channel member 29 is secured to the vertical strip 28 by fastening members 30.

A second wooden strip 31 is secured to the inner face 11 of the block 10 and to the strip 28 and plaster 32 is adapted to be mounted on the inner face 11 of the block 10 and if desired may cover the inner face of the strip 31 and the inner edge of the strip 28 and also extend in the space between the inner edge of the channel 29 and the inner edge of the strip 28 as shown in dotted lines in Figure 1.

In the use of this block structure, the concrete blocks 10 are cast in the usual manner in forms provided for that purpose. These forms will include means for holding the metal strip 20 and the anchoring means 21—22 which are initially embedded in the metal strip 20. In this manner when the concrete sets the anchoring 55

members 21—22 will be firmly anchored in the body of the block 10 and the inner face of the strip 20 will snugly engage the angled face portions 17 of a block 10.

5. When these blocks are placed on opposite sides of the window opening in superposed relation, a pair of vertically disposed soft metal strips will be provided to which the window frame member 23 may be secured. These blocks 10 may be also 10 mounted across the upper edge of the window opening and if desired, may also be mounted on the sill or lower portion of the window opening. Where this is done, a substantially continuous soft metal strip is provided entirely around the 15 window opening to which the window frame may be secured.

What I claim is:

1. In building construction a non-metallic wall block having an outer side face formed with an 20 inset forward portion and an outer end face formed with a portion inset with respect to the outer part of said forward portion, a soft metal strip positioned against said forward portion, and means for anchoring the strip and block together.
- 25 2. In building construction a non-metallic wall block having an outer side face formed with an inset forward portion and an outer end face formed with a portion inset with respect to the outer part of said forward portion, a soft metal strip positioned against said forward portion, and means for anchoring the strip and block together, said strip corresponding in width and length to the 30 said inset forward portion and having an edge flush with a part of said end face.
- 35 3. In building construction, a hollow concrete wall block having an outer end face provided with front and rear rabbets, said block having an outer side face formed with a non-inset rear portion and an inclined inset forward portion 40 merging into said end face at one side of said front rabbet, a soft metal strip of triangular cross section disposed throughout said inclined portion and inset with respect to the said non-inset portion, and means for anchoring said strip to said block.
- 45 4. In building construction, a hollow concrete wall block having an outer side face formed of a non-inset rear portion and an inclined inset forward portion, a soft metal strip of triangular

cross section disposed throughout said inclined portion and inset with respect to said non-inset portion, and means for anchoring said strip and block together.

5. In building construction, a hollow concrete 5 wall block having an outer side face formed of a non-inset rear portion and an inclined inset forward portion, a soft metal strip of triangular cross section disposed throughout said inclined portion and inset with respect to said non-inset 10 portion, and Y-shaped means having its V and a portion of its stem embedded in said block and the remaining portion of its stem embedded in said strip for anchoring the latter to the block.

6. In building construction, a hollow concrete 15 wall block including an outer end face and an outer side face, said outer side face being formed of a substantially straight rear portion, an inwardly extending rounded intermediate rear portion, an inset concaved intermediate front portion and an inclined inset forward portion disposed at an angle to said concaved portion, said straight portion merging into said rounded portion, said rounded portion merging into said concaved portion, said concaved portion merging into said inclined portion, said inclined portion merging into one side of said end face, a soft metal strip of triangular contour seated throughout against said inclined surfaces and flush with one side of said outer end face, and means embedded in the block and strip for anchoring them together.

7. In building construction, a hollow concrete wall block having an outer end face and an outer side face, said outer side face being formed with 35 a straight portion, an inwardly extending curved portion merging at its rear side into the forward side of said straight portion and an inclined portion merging at its rear side into the forward side of the curved portion and at its outer side 40 into one side of said outer end face, said inclined portion being inset with respect to said straight portion and disposed at an angle to said curved portion, a soft metal strip of triangular cross section disposed throughout said inclined 45 portion and having one of its sides disposed in a line parallel to said straight portion, and means for anchoring said block and strip together.

HARLEY D. GUSTINE.
